UNITED STATES PATENT OFFICE.

PETER A. OSHANYK, OF WILTON, NORTH DAKOTA.

TIMER.

1,409,062.

Specification of Letters Patent.

Patented Mar. 7, 1922.

Application filed January 14, 1921. Serial No. 437,261.

To all whom it may concern:

Be it known that I, PETER A. OSHANYK, a citizen of the United States, residing at Wilton, in the county of McLean and State 5 of North Dakota, have invented certain new and useful Improvements in Timers, of which the following is a specification.

This invention relates to timers for internal combustion engines, and it comprises 10 a supporting bracket, a lever pivotally mounted thereon, one end of said lever forming a contact, a cam engaging the end of said lever, a slidable rod engaging said cam, connecting means between the said slidable rod 15 and said lever to intermittently separate said contact and cam, and speed controlled means for rendering the mechanism inoperative.

In the present invention, I have provided a timer for gas engines of the jump spark 20 type, wherein the parts are of simple construction and are very unlikely to get out of order. The contact is made between a cam and a pivoted lever, and means are provided, also operated by the same cam, to swing the 25 pivoted lever at regular intervals and thus separate the contact end of the lever and cam.

I have further provided means for maintaining the contact end of the lever and the 30 cam spaced when the speed of the engine exceeds a predetermined limit. A governor operated by the engine at a speed proportional to the engine speed is connected to the slidable rod and is adapted to actuate said 35 rod and the connecting means of the pivoted lever, whereby the contact end of the lever will remain separated from the cam when the speed of the engine exceeds the speed for which the governor is set.

40 In the accompanying drawings, I have shown one embodiment of the invention. In this showing:

Figure 1 is a side elevation showing the timer applied,

45 Figure 2 is a sectional view on line 2—2 of Figure 1,

Figure 3 is a similar view on line 3—3 of Figure 1,

Figure 4 is a similar view on line 4—4 50 of Figure 1,

Figure 5 is a detail perspective view of the timer, and,

Figure 6 is a sectional view on line 6—6 of Figure 5.

55 Referring to the drawings, the reference numeral 1 designates generally, an engine

mounted on a base 2, and provided with a spark plug 3. The plug is energized by the coil 4 which is connected thereto by means of a connection 5, the circuit being grounded 60 on the engine cylinder by connection 6. A source of energy 7 is connected to the coil by connection 8, the other terminal of the battery or other source of energy being connected to the timer. The parts heretofore 65 described are of the usual construction and form no part of the invention except in the combination claimed.

The timer comprises a supporting bracket 10, one end of which is supported on a portion of the engine, as at 11. A depending arm 12 is arranged on the other end of the bracket, and this arm is secured to the supporting member 13, arranged on any suitable support. As shown, the supporting member 70 13 forms one of the bearings of the main crank shaft 14. A lever 15 is pivoted to the supporting bracket, as at 16, the end of the lever being secured to an arm 17, slidably mounted on the depending portion 12 of the 75 supporting bracket. The arm is maintained in position with respect to the bracket, by means of a clip 17' embracing the arm 17, and the depending portion 12. This clip may be secured to the arm by any suitable 80 means, such as bolt and nut 18. The lower end of the arm is offset, as at 19, and is provided with a contact member 20. The lead wire 9 passes through an insulating tube 21 arranged on the pivoted lever and is connected to the contact 20. A cam 22 is arranged on a shaft 23 driven from the main crank shaft in any suitable manner, and this cam normally contacts with the contact member 20, the members being maintained in 85 contact by a spring 24, one end of which is secured to bearing 13 and the other end to a hook 25, formed on the end of the slidable arm 16. A slidable member 26 is mounted in suitable guides 27 carried by the engine 90 or engine frame, and this member is provided with a roller 28 which also engages the cam 22. A sleeve 29 surrounds the slidable member and is maintained in adjusted position thereon by a set screw 30. This sleeve 95 is provided with a pair of ears for the reception of one end of a connecting member 31, the other end of which is secured to the pivoted lever, as at 32. The connecting member is provided with a turn-buckle 33, where- 100 by the length may be varied.

A shaft 34 mounted in bearings 35, is

- driven from the main crank shaft in any suitable manner. This shaft is provided with a governor, comprising a pair of sleeves 36 and 37. The sleeve 36 is secured to the shaft and the sleeve 37 is slidably mounted thereon and prevented from rotating by a key 38. Links or arms 39 are secured to the sleeves and are provided with weights or balls 40.
- 10 The sleeve 37 is connected to the slidable member 26 by an arm 41. As shown (see Figure 6), the slidable member is provided with a slot 42 for the reception of a bolt or pin 43, carried by the arm 41.
- 15 The operation of the device is as follows: The arm 16 being slidably mounted on the depending portion of the bracket 10 is normally maintained in its lowered position with the contact 20 and the cam 22 in engagement by spring 24, secured to the arm, at 25. Upon each revolution of the shaft 23, the cam moves the slidable member 26 to the left, in Figure 1 of the drawings, and swings the pivoted lever 15 on its pivot, raising the arm 16 against the tension of spring 24 and separating the contact 20 from the cam. In normal operation of the engine, the circuit is intermittently opened and closed in this manner, permitting the spark plug 3 to be actuated in the usual manner.
- 20 When the speed of the engine exceeds a predetermined limit, and the balls or weights 40 are moved outwardly by centrifugal force, the sleeve 37 is moved toward the sleeve 36 and the slidable member is moved to the left, in Figure 1 of the drawings, through the connection 41. This depresses the pivoted lever at the point where it is secured to the connecting element 31 and raises the arm 16 to separate the contact 20 and cam 22. The contacts will remain broken until the speed of the engine decreases and the slidable sleeve 37 assumes its normal position. The slot 42 in the slidable member 26 is provided to permit normal operation of the timer without affecting the governor. When the slidable member is actuated by the cam in normal operation, the pin 43 rides from one end of the slot to the other, without changing the position of the connecting member 41.
- 25 It is to be understood that the form of my invention herewith shown and described is to be taken as a preferred example of the same, and that various changes in the shape, size, and arrangement of parts may be resorted to without departing from the spirit of the invention or the scope of the subjoined claims.
- Having thus described my invention, I claim:
- 30 1. A timer, comprising a pivoted lever, a contact carried by said lever, a revolving cam normally engaging said contact, and a control member actuated by said cam and adapted to move said pivoted lever to separate said contact and said cam.
2. A timer, comprising a pivoted lever, a contact carried by said lever, a revolving cam normally engaging said contact, a control member actuated by said cam, and adapted to move said lever to separate said contact and said cam, and speed control means adapted to actuate said control member independently of said cam.
3. A timer, comprising a pivoted lever, a contact carried by said lever, a revolving cam arranged near said contact, a coil spring normally retaining said cam and said contact in engagement, and a control member actuated by said cam and adapted to move said contact out of engagement with said cam.
4. A timer, comprising a pivoted lever, a contact carried by said lever, a revolving cam arranged near said contact, a coil spring normally retaining said cam and said contact in engagement, a control member actuated by said cam and adapted to separate said contact and said cam, and speed control means for actuating said control member independently of said cam.
5. In a timer, a supporting bracket, a lever pivotally mounted thereon, said bracket being provided with a depending portion, an arm connected to said lever and slidably mounted on the depending portion of said bracket, the end of said arm being provided with a contact member, a cam normally engaging said contact member, a slidably mounted member engaging said cam, and connections between said slidably mounted member and said pivoted lever to intermittently move said lever and separate said contact member and said cam.
6. In a timer, a supporting bracket, a lever pivotally mounted thereon, said bracket being provided with a depending portion, an arm connected to said lever and slidably mounted on the depending portion of said bracket, the end of said arm being provided with a contact member, a cam normally engaging said contact member, a slidably mounted control member engaging said cam, connections between said control member and said pivoted lever to intermittently move said lever and separate said contact member and said cam, and speed operated mechanism connected to said control member to separate said contact member and said cam when the speed exceeds a predetermined limit.
- In testimony whereof, I affix my signature in presence of two witnesses.
- PETER A. OSHANYK.
- Witnesses:
- A. M. DAHL,
L. E. MASSEY.
